UNITED STATES PATENT OFFICE.

ERNEST ROWLAND HILL, OF EAST ORANGE, NEW JERSEY, ASSIGNOR TO THE WESTINGHOUSE AIR BRAKE COMPANY, OF PITTSBURGH, PENNSYLVANIA, A CORPORATION OF PENNSYLVANIA.

TRIP-VALVE DEVICE.

1,133,644.

Specification of Letters Patent. Patented Mar. 30, 1915.

Application filed May 10, 1911. Serial No. 626,321.

To all whom it may concern:

Be it known that I, ERNEST ROWLAND HILL, a citizen of the United States, residing at East Orange, in the county of Essex and 5 State of New Jersey, have invented new and useful Improvements in Trip-Valve Devices, of which the following is a specification.

This invention relates to trip valve devices for use in controlling trains automatically 10 and is adapted to be operated by a trip mechanism located along the track to vent air from the train brake pipe to apply brakes, and shut off the supply of motive fluid from the motors when the vehicle runs 15 past a signal set at danger.

One of the objects of my invention is to provide an improved trip valve device of this character, which shall be of simple and durable construction and adapted to hold 20 the vent valve open until the train pipe pressure has fallen to a predetermined degree.

Another object is to utilize the air thus vented from the train pipe for operating a device for closing the throttle valve or 25 other motive power controller.

As shown in the accompanying drawing, Figure 1 is a sectional view of one form of my improved trip valve device; Fig. 2, a similar view showing a slightly modified construction; Fig. 3, a view, mostly in section, of a throttle valve closing device operated by the air vented from the train pipe by the trip valve; and, Fig. 4, a sectional view of a modified form of throttle closing device.

35 As shown in Fig. 1, my improved trip valve device comprises a casing having a connection, 10, for communication with the train brake pipe and containing a valve, 9, which, as shown, is of the slide valve type, 40 and is operated by a pin, 4, extending through a slot in the valve seat and connected to the main stem 5 having the striking head, 6. The stem is provided with a piston head, 7, having a snug fit in its cylinder and subject to the adjustable spring, 8, which tends to hold the stem and valve in the normal closed position. The cylinder space above the piston, 7, communicates with the atmosphere through a small port 4 so 45 that the air in said chamber acts as a cushion to the upward movement of the stem, 5.

When the stem is raised by the trip mechanism along the track, the piston is forced upward, compressing the spring, 8, and opening the vent valve, 9. As the air under pressure from the train pipe then flows out through the escape pipe, 11, the pressure which builds up on the lower side of piston, 7, is sufficient to hold the same raised with the valve open until the train pipe pressure 55 has diminished to a predetermined degree at which the spring, 8, overcomes the pressure under piston, 7, and the valve is then returned to closed position. In this way the 60 brakes are automatically applied and the 65 train brought to a stop.

In the construction shown in Fig. 2, the vent valve 9^a is shown as of the puppet type, mounted directly upon the stem, 5, but the operation is substantially the same as above 70 described. The piston, 7, may be normally located below the discharge outlet in order to be assisted in the upward movement by the air flowing from the train pipe through the train pipe and passage, 10^a. If desired, 75 a diaphragm, 11^a, having a restricted opening may be located at the discharge outlet for causing the pressure to build up upon piston, 7.

According to another feature of my improvement, the air discharged from the train pipe through the vent valve is utilized for closing the throttle valve, or cutting off the supply of fluid to the motor propelling the vehicle, and one form of such mechanism is 80 shown in Fig. 3, in which the supply of steam or other fluid to the motor is controlled by a valve 23, having a stem, 22, and a spring, 25, for closing the valve. The valve is normally held open by a latch, 20, 85 engaging a collar, 21, on the stem, 22, but said latch is adapted to be released by the piston, 18, when fluid under pressure is admitted to the same, thereby compressing spring, 19, and allowing the spring, 25, to 90 close the valve, 23. The valve may then be 95 closed and reset by the handle, 24.

In order to control the pressure operated latch by the air discharged from the train pipe through the vent valve, a vane or flap 100 valve, 12, may be pivotally mounted at the end of the discharged pipe, 11, in such a

manner that the air in discharging turns the vane and lever, 13, to actuate small valves 15 and 16 which control the supply of fluid under pressure from pipe, 17, through pipe 26, to the piston, 18, and its release therefrom to the atmosphere. The end of the discharge pipe may be covered by a perforated screen, 14. When the train pipe vent valve is opened, and the air is discharged through pipe, 11, against the vane, 12, the same moves to close the exhaust valve, 15, and open supply valve, 16, whereupon the piston, 18, is actuated by the pressure to release the latch and permit the closing of the main supply 23, thereby bringing the train to a sudden stop.

According to the construction shown in Fig. 4, the throttle is in the form of a piston valve, 33, having a reduced portion, 34, and being continuously exposed at one end to the pressure in chamber, 32, which communicates with the source of supply. The pressure in chamber, 31, at the opposite end of the piston valve is controlled by a small valve, 28, having a stem, 40, connected to piston, 39, located in a chamber communicating with the discharge pipe, 11. Pressure from the source of supply admitted through the passage, 29, normally holds the valve, 28, with the exhaust, 38, closed and communicates through port, 30, with the chamber, 31. As a stem or rod, 38, is connected to the opposite end of the piston valve, the area exposed to the pressure in chamber, 31, is slightly larger than the effective area of the piston exposed to the pressure in chamber, 32, and the piston valve, 33, will therefore normally occupy the open position as shown. When the air from the train pipe is discharged through the vent valve and the pipe, 11, against the face of piston, 39, the same is moved upward to open the escape ports, 37, to the atmosphere. At the same time, the valve, 28, closes the admission port, 29, and opens exhaust port, 36, whereupon the pressure escapes from chamber 31, and the pressure in chamber 32, at the opposite end of the piston valve, 33, shifts the same to closed position, and cuts off the supply of steam or other fluid to the motors. After the pressure has escaped from the train pipe, the valve, 28, may be reset by the hand lever, 35, and, if desired, the piston valve, 33, may also be manually adjusted by means of the rod connection, 38.

It will be apparent that any suitable form of vent valve device, such as an ordinary trip cock, 9, shown in Fig. 3, may be employed in connection with the feature of my improvement relating to the use of the air vented from the train pipe for controlling the cutting off of the supply of motive fluid. If it is desired to sound an alarm in the locomotive cab or within the hearing of the motorman at the same time that the trip

valve is operated, this may be conveniently accomplished by attaching a whistle 41 to the pipe 26 so that the fluid under pressure will operate to sound the alarm when the valve 16 is opened by the air vented from the train pipe.

While I have described more or less in detail, certain specific devices for accomplishing the desired results, it will be understood that my invention is not limited to any particular form of construction as it is apparent that various other modifications of fluid pressure means governed by the discharge of air from the train pipe through the vent valve may be designed without departing from the spirit and scope of my invention.

Having now described my invention, what I claim as new and desire to secure by Letters Patent, is:

1. In a trip valve device for air brakes, the combination with a vent valve for controlling the discharge from the train pipe, and a connection adapted to be operated by a trip mechanism along the track for opening said valve, of means governed by the pressure of air vented through said valve for maintaining the same open a certain length of time.
2. In a trip valve device for air brakes, the combination with a vent valve for controlling the discharge from the train pipe, and a connection adapted to be operated by a trip mechanism along the track for opening said valve, of a movable abutment subject to the pressure of the air vented through said valve for holding the same open until the train pipe pressure has diminished a predetermined amount.
3. In a trip valve device for air brakes, the combination with a vent valve for controlling the discharge from the train pipe, and a connection adapted to be operated by a trip mechanism along the track for opening said valve, of a movable abutment connected to said valve and subject on one side to the pressure of the air vented through said valve, and an opposing spring tending to close the valve.
4. In a trip valve device for air brakes, the combination with a train pipe, a vent valve for controlling the discharge from the train pipe, and a connection adapted to be operated by a trip mechanism along the track for opening said valve, of a power controller having fluid pressure mechanism for controlling the closing of the same, and a movable abutment operated by the air discharged from the train pipe through the vent valve for governing the action of said fluid pressure mechanism.
5. In a trip valve device for air brakes, the combination with a train pipe, a vent valve for controlling the discharge from the train pipe, and a connection adapted to be operated by a trip mechanism along the

track for opening said valve, of a throttle valve having a fluid pressure device for controlling the closing of said throttle valve, and means operated by the air discharged 5 from the train pipe through the vent valve for governing the action of said device.

In testimony whereof I have hereunto set my hand.

ERNEST ROWLAND HILL.
